CONDENSER FOR INTERNAL-COMBUSTION ENGINES

Application filed April 13, 1926. Serial No. 101,725.

The object of our invention is to provide a condenser applicable for use in steam cooling systems for internal combustion engines, said condenser comprising juxtaposed direct and reflux steam condensing units of novel construction and arrangement, and simple and inexpensive to manufacture.

A practical embodiment of our invention is represented in the accompanying drawings which represent the condenser in longitudinal vertical section.

The condenser herein shown comprises juxtaposed direct and reflux condensing units having separate upper chambers and a lower chamber common to both units.

The direct condensing unit of the condenser comprises passages 1 connecting the upper chamber 2 with the common lower chamber 3, the said upper chamber having a steam inlet port 4.

The reflux condensing unit of the condenser is located immediately in front of the direct condensing unit and comprises passages 5 connecting the upper chamber 6 with the said common lower chamber 3, the said upper chamber 6 of the reflux condensing unit having a removable filling cap 7 and also a vent 8 to external atmosphere. The common lower chamber 3 is provided with an escape port 9 for the water of condensation. A water overflow passage 10 may be provided for the common lower chamber 3 so that a specified quantity of water may be supplied to the system when desired, the chamber end of which passage is normally water sealed so that the steam will be caused to pass upwardly through the reflux condensing unit rather than permitted to escape through the said overflow passage.

A drain cock 11 is provided for the common lower chamber 3 of the direct and reflux condensing units.

In the present instance a single hollow casing 12 is provided with a partition 13 to form the upper chambers 2 and 6 of the direct and

reflux condensing units, and a single hollow casing 14 is provided for the common lower chamber 3 of the direct and reflux condensing units.

In operation:—The steam entering the upper chamber 2 of the direct condensing unit is more or less condensed in the passages 1, the water of condensation gathering in the common lower chamber 3. The water of condensation may be drawn off from this chamber through the passage 9. If more steam is being generated than can be condensed in the direct condensing unit, it will pass upwardly from the chamber 3 through the passages 5 into the upper chamber 6 where such steam as has not been condensed in the reflux condensing unit will escape to external atmosphere through the vent 8. It will be understood that this reflux condensing unit is arranged in the coldest part of the system in front of the direct condensing unit so that the greatest practicable amount of steam will condense and join the water of condensation in the common lower chamber 3.

It will be understood that the passages 1 and 5 of the two condensing units may be of any well known or approved form.

Where a specified quantity of water is required to be supplied to the system, the overflow passage 10 is provided, the end of which passage which is located in the chamber 3 being arranged to be normally sealed by the water in said chamber so that the steam will be caused to pass upwardly through the reflux condensing unit. With other systems, the overflow passage may be omitted, the vent 8 being sufficient for the outward passage of the air during the heating period and for its return during the cooling period.

While describing this condenser in connection with water it is to be understood that any suitable liquid may be utilized.

It is evident that various changes may be resorted to in the construction, form and arrangement of the several parts without de-

parting from the spirit and scope of our invention; hence, we do not intend to be limited to the particular embodiment herein shown and described, but what we claim is:—

5 1. An air cooled steam condenser for use in connection with internal combustion engines where the steam generated in the engine water jacket by the heat of the engine is condensed by the cooling effect of the air 10 on the condenser, said condenser comprising direct and reflux condensing passages, the upper chamber of the direct condensing unit having a steam inlet port, the common lower chamber for the direct and reflux condensing units having an outlet port for the water of condensation, and also a water overflow passage having its upper outside end located near the top of the lower chamber and its lower inside end located normally 20 below the water level in the lower chamber whereby any steam which may not be condensed in the direct condensing unit may pass from the lower chamber upwardly into the reflux condensing unit without escaping 25 through the overflow passage.

2. An air cooled steam condenser for use in connection with internal combustion engines where the steam generated in the engine water jacket by the heat of the engine 30 is condensed by the cooling effect of the air on the condenser, said condenser comprising direct and reflux condensing passages, the upper chamber of the direct condensing unit having a steam inlet port, the common lower 35 chamber for the direct and reflux condensing units having an outlet port for the water of condensation, and also a water overflow passage having its upper outside end located near the top of the lower chamber and its lower inside end located normally below the 40 water level in the lower chamber whereby any steam which may not be condensed in the direct condensing unit may pass from the lower chamber upwardly into the reflux condensing unit without escaping through the 45 overflow passage, the upper chamber of the reflux condensing unit having a vent to external atmosphere.

3. An air cooled steam condenser for use 50 in connection with internal combustion engines where the steam generated in the engine water jacket by the heat of the engine is condensed by the cooling effect of the air on the condenser, said condenser comprising direct and reflux condensing passages, the upper 55 chamber of the direct condensing unit having a steam inlet port, the common lower chamber for the direct and reflux condensing units having an outlet port for the water of 60 condensation, and also a water overflow passage having its upper outside end located near the top of the lower chamber and its lower inside end located normally below the 65 water level in the lower chamber whereby any steam which may not be condensed in the

direct condensing unit may pass from the lower chamber upwardly into the reflux condensing unit without escaping through the overflow passage, the upper chamber of the reflux condensing unit having a vent to external atmosphere, and also a water filling opening.

In testimony, that we claim the foregoing as our joint invention, we have signed our names this 12th day of April, 1926.

IRA HUBERT AYRES.
